UNITED STATES PATENT OFFICE.

CONRAD JOBST, OF TOLEDO, OHIO, ASSIGNOR TO THE TOLEDO AUTOMATIC BRUSH MACHINE COMPANY, OF TOLEDO, OHIO, A CORPORATION OF OHIO.

BRUSH MACHINE.

Application filed February 19, 1925. Serial No. 10,290.

The invention relates to brush machines of that type designed to perform only the tufting operation on previously bored brush backs, and it is the primary object to obtain a construction which may be used either for hand filling operation or for automatic filling of brush backs of various sizes and patterns. To this end the invention consists in the means employed for effecting the successive registration of the holes in the back with the tufting nozzle as hereinafter set forth.

In the drawings:

Figure 1 is a side elevation of the machine;

Figure 2 is an elevation at right angles to Fig. 1;

Figure 3 is a perspective view of the work holder;

Figure 4 is a section on line 4—4 of Fig. 5;

Figure 5 is a section on line 5—5 of Fig. 4;

Figure 6 is a sectional plan view on line 6—6 of Fig. 2;

Figure 7 is a cross section on line 7—7 of Fig. 2.

In general construction the machine comprises a frame or pedestal 1 on the upper portion of which is mounted a tufting unit, including a bristle holding magazine 2, tuft separating needles 3, a reciprocatory tuft setting nozzle 4, wire feeding mechanism 5 and other auxiliary parts for forming the tuft securing staples engaging the same with the tuft and driving the staple and tuft in a registered hole in the brush back. As the unit thus briefly described is the same in general construction as in my previous application Serial No. 527,590, filed January 7, 1922, it is unnecessary to describe the same more in detail.

The brush backs to be filled with tufts are previously bored in any suitable machine, such as a multiple drill which will insure exact relative positions of the holes in any predetermined pattern. As brushes are made in a large variety of patterns differing in number of tufts and the arrangement of the same, I have devised a construction of automatic feeder which may be quickly adjusted for such variations, the construction being as follows: secured to the pedestal is a work holding table or shelf

6, which may be raised or lowered by the 55 adjusting screw 7 and clamped in position by the clamping screw 8. Upon this table or shelf is mounted a frame 9, on the upper end of which is a horizontally movable frame 10 with an anti-friction support 60 formed by the raceways 11 and ball 12. Upon the frame 10 there is arranged a transversely movable table 13 with an anti-friction support formed by the raceways 14 and balls 15. Thus the table is capable of 65 movement in one direction on the frame 10 and together with said frame is movable in a transverse direction on the frame 9. Beneath the frame 10 there is journaled in the frame 9 the vertical shaft 16 adapted 70 to receive at its upper end the cams 17 and 18, which are keyed thereto and secured by the cap screw 19. The shaft 16 is driven through the medium of bevel gears 20, 21, from a shaft 22, which extends to one side 75 of the frame 9 and has mounted thereon the change gear 23. This gear is driven by a pinion 24 on a shaft 25 journaled in bearings on a plate 26, which is adjustably secured to the frame 9 by the set screw 27 80 passing through the slot 28 in said plate, the arrangement being such that the pinion may be shifted in position so as to be placed in proper mesh with change gears of varying diameters. The shaft 25 is driven 85 through the bevel gear wheels 29 and 30 from a shaft 31, which has a splined engagement with a bevel gear wheel 32 journaled in a bearing 33 on the frame 9. There is also a yoke connection 34 between the 90 shafts 25 and 31 by which these shafts and the gears 29 and 30 will travel together in the adjustment of the plate 26, this being permitted without moving the bevel gear 32 by reason of the spline engagement. The 95 bevel gear 32 is driven by the bevel pinion 35 on a vertical shaft 36, which in turn is driven through the bevel gear wheels 37 and 38 from the shaft 39 of the tuft setting unit. This shaft is driven through the pulley 40 from any suitable source of power. The shaft 36 is preferably made in two parts 36^a and 36^b, which are normally clamped together by a clamp or coupling 60. This clamp may be loosened in order 100 to change the timing of the cams with respect to the tuft setting mechanism.

The train of mechanism just described

will transmit rotary motion from the shaft 39 to the shaft 16 and from the latter to the cams 17 and 18 mounted thereon. The cam 18 is in engagement with a bearing finger 41 upon the frame 10 so as to transmit movement to said frame yieldably resisted by the spring 42, while a finger 43 depending from the table 13 engages the cam 17 and is actuated thereby against the yieldable resistance of the spring 44. The spring 42 has one end thereof attached to the slideable frame 10 as indicated at 42^a, while the other end is suitably secured to the fixed frame 9, as indicated at 42^b. One 15 end of spring 44 is secured to the table 13 at 44^a and the other end to the frame 10 at 44^b. Thus the position of the table 13 at each point in the rotation of the shaft 16 is determined by the shape of the 20 cams and any desired movement may be imparted to said table by properly fashioning said cams.

Any suitable work holder may be mounted upon the table 13 to secure the brush backs 25 which are to be operated upon. Preferably this work holder comprises a slide 45 mounted in guideways 46 on the table and movable between stops into two different positions. As shown, the stops are shoulders 30 45^a at the ends of a recess 45^b in the underside of the slide 45. A pin 46^a projects into this recess and is adapted to alternatively engage the shoulders 45^a. On the slide is a pair of work holding clamps 47 in which 35 the brush backs, such for instance as tooth brush handles, may be inserted. These clamps may be properly registered with the tufting mechanism by moving the slide to its opposite limits, so that during the time 40 of the tufting of the back in one of the clamps the work may be removed and replaced in the other clamp.

The machine is started by the throwing in of a clutch 48 controlled by the trip rod 49 actuated by the pedal lever 50 and the stopping of the machine is effected by a lever 51 actuated by a pin 52 on the cam 18. The lever 51 normally operates as a latch for holding the rod 49 in depressed position 50 against the tension of a returning spring 53, but the movement of said lever under actuation of the pin 52 disengages this latch and permits the rod 49 to disengage the clutch 48, thereby stopping the machine.

55 In operation, to tuft a brush back of any desired pattern, the proper cams are selected and engaged with the shaft 16. A corresponding change gear 23 is also selected and engaged with the shaft 22 and the plate 26 is adjusted to properly mesh the pinion 24 with the change gear 23. When thus adjusted a bored brush back is inserted in one of the clamps 47 and the machine is started by the operation of the lever 50. This will cause the reciprocation of the nozzle 4 to-

wards and from the brush back and the ejection of a tuft from said nozzle into engagement with the registering hole in the back. Each time the nozzle is withdrawn the cams 17 and 18 operate to shift the table and the brush holder thereon so as to bring another hole in registration with the nozzle when it is again moved downward. Preferably the cam 18 shifts the table for the successive rows of bristles, while the cam 17 adjusts the table 75 step-by-step for the successive holes in each row. When the last hole is filled, the tripping of the lever 51 by the pin 52 releases the clutch 48 and arrests further movement of the machine. 80

The operator then shifts the slide 45 to bring the second brush back in registration with the tufting mechanism and again operates the lever 50 to start the machine, after which the finished brush may be removed 85 from its clamp 47 and a new drilled back inserted in this clamp ready for another operation.

What I claim as my invention is:

1. The combination with tuft setting 90 mechanism, of a laterally movable work support, cooperating cams for moving said work support in transverse directions, mechanism for driving said cams in timed relation to said tuft setting mechanism, and a work 95 holder having a pair of brush retaining means mounted on said support and slidably movable independently of said support between stops thereon to alternatively bring either of said retaining means into operative 100 relation to said tuft setting mechanism, whereby a finished brush may be withdrawn from the holder out of registration with the tuft setting mechanism and a new brush back inserted therein during the operation 105 of said mechanism on the work in the holder in registration therewith.

2. In a brush making machine, the combination with a reciprocable tool for operating on a brush back, of a laterally movable 110 work support, a removable cam for operating said work support step by step through a complete cycle, mechanism for operating said cam in timed relation to said tool, including a removable gear and a second gear 115 cooperating therewith, said removable gear having teeth corresponding to the number of steps in a complete cycle, and means for laterally adjusting the axis of said second gear with respect to said removable gear. 120

3. In a brush making machine, the combination of a vertical reciprocable tuft setting mechanism, rotary means for driving said tuft setting mechanism, a work carrying table movable horizontally in transverse directions, a vertical spindle beneath said work carrying table, a pair of cam plates detachably connected to said spindle, said cam plates being provided with a series of steps connected by inclined portions, cam fol- 130

lowers respectively cooperating with said cam plates, a removable gear connected to said spindle, a second gear meshing with said removable gear, a movable support for 5 said second gear permitting lateral adjustment of the axis thereof with respect to said removable gear, a driving mechanism be-

tween said rotary means and said second gear, and a coupling in said driving mechanism permitting adjustment of the timing 10 of said cams relative to said tuft setting mechanism.

In testimony whereof I affix my signature.

CONRAD JOBST.
